UNITED STATES PATENT OFFICE.

ALFRED OWEN CROZIER, OF NEW YORK, N. Y., ASSIGNOR TO CROZIER-STRaub, INC., OF NEW YORK, N. Y., A CORPORATION OF NEW YORK.

MACHINE FOR MAKING CEMENTITIOUS ARTICLES.

Application filed May 22, 1920. Serial No. 383,501.

To all whom it may concern:

Be it known that I, ALFRED OWEN CROZIER, a citizen of the United States of America, residing at New York, in the 5 county and State of New York, have invented certain new and useful Improvements in Machines for Making Cementitious Articles, of which the following is a full, clear, and exact description.

10 This invention relates to the manufacture of cementitious or concrete articles, such as brick, tile, pipe, building blocks, etc. More particularly it relates to the manufacture of such articles by methods in which a shaped 15 mass or body of concrete of rectangular, circular or other suitable cross section is formed and then cut up or subdivided into smaller articles. The body or mass of concrete from which such portions are severed 20 can be conveniently produced by the so-called column method. In this method an upright hollow shaft or container is provided, of which at least the lower portion has the desired cross sectional size and con- 25 tour. The shaft is filled with (preferably) "wet" concrete, up to such height that the weight of the superincumbent mass upon the lower portion will exert a marked compacting, or "densifying," and unwatering effect 30 on the lower portion, from which latter successive sections are removed, the column in the shaft descending after such removal and being maintained at the proper height by the continuous or intermittent addition of 35 fresh concrete of suitable consistency.

Heretofore my practise has been to use one or more knives to sever and cut up or divide the more or less compacted portion of the column. A clean cut is thus produced, 40 with the additional advantage that the movement of the knives has a "trowelling" effect on the surfaces of the concrete articles, making said surfaces denser and less porous. The knives, however, suffer con- 45 siderable wear, and for certain purposes the smooth, "slick" finish imparted by the knives is not desirable, as for example, on brick, tile, or other concrete articles upon which plaster or stucco or the like is to be 50 applied.

In a copending application Serial No. 275,696, filed February 8, 1919, I have described a cutter means for unset concrete, which includes a wire or wires, which may 55 be twisted or provided with roughening pro-

jections. The wires are preferably operated in a manner of a saw to sever the unset concrete and produce the desired rough surface.

The objects of the present invention reside in the provision of a machine for making hollow or solid concrete articles by the so-called column method. In this machine the improved cutters described in my copending application are utilized for severing the article and for thereafter subdividing it into a plurality of smaller articles. The advantages attendant upon the use of these cutters are fully set forth in the application above referred to.

Other objects of the invention reside in 70 the provision of certain operating mechanism for the various machine parts including the cutters, whereby the articles may be produced and delivered rapidly and at a minimum of labor and expense.

Other objects of the present invention will be set forth in more detail in the accompanying specification and shown in the drawings, in which—

Fig. 1 shows a front view of the machine 80 with certain parts shown in section.

Fig. 2 is a side elevation of the machine.

Fig. 3 is a sectional view taken on line 3—3 of Fig. 1.

Fig. 4 is a top plan view of the machine 85 and shows the operating cams and driving connections.

Fig. 5 is a sectional view taken on line 5—5 of Fig. 3.

Fig. 6 is a sectional view showing the position of the parts just after the withdrawal 90 of the supporting plate and with the core about to descend.

Fig. 7 shows the position of the parts with the machine at rest.

Figs. 8 and 9 show details of the clutch construction.

Fig. 10 is a section taken on line 10—10 of Fig. 2 and illustrates the cross cutting wires and operating mechanism and supporting plate structure.

Fig. 11 is a detail sectional view taken on line 11—11 of Fig. 10.

Fig. 12 is a detail sectional view taken on line 12—12 of Fig. 5.

Fig. 13 shows a detail view of a modified form of cutter in which the supporting plate is used for the dual purpose of a cutter and support.

Fig. 14 is a detail sectional view of the 110

parts shown in Fig. 13 taken on line 14—14.

In more detail, 10 represents the frame work of the machine. Suitably supported in this frame is a hollow vertical container 5 element 11 which is provided with a funnel shaped top to receive slushy or wet concrete. The concrete within the container is more or less compacted and unwatered by its own weight and formed into an unset cementitious column here shown as having a rectangular cross section. Within the container are a number of core elements 12 supported by a cross member 12^a adapted to be slidably supported in guides 13. The number of 10 these cores and their shape may be varied depending upon the shape of the desired product. They may also be omitted if solid articles are desired. The cores are preferably fastened together and positioned in the 15 container by members 14 best shown in Fig. 3.

Below the open lower end of the container and spaced slightly therefrom is a mold section 15 which is supported upon the frame 20 of the machine. Closing the bottom of the mold section is a displaceable pallet 16.

Supported upon a frame 17 (Fig. 4) at the top of the machine is a shaft 18 carrying a belt pulley 19 receiving power by means 25 of a belt from a power source such as a motor (not shown). Shaft 18 carries a pinion 20 which meshes with and drives a gear 21 rotatably mounted upon a shaft 22 which forms the main operating shaft of the machine (see Figs. 1 and 4). Gear 21 is shaped 30 to form one element of a cone clutch (see Figs. 8 and 9). The other element 23 is splined on shaft 22 and is adapted to be engaged with the gear clutch element by means 35 of a coil spring 24. This element is provided with a collar portion and a camming projection 25 is provided. A pawl lever 26 pinned on clutch control shaft 27 is adapted to engage this camming projection and dis- 40 engage the clutch and stop the rotation of shaft 22 (see Fig. 8). By drawing down on a control rod 28 the pawl lever will be swung clear of the camming projection and permit the clutch to be engaged. The control rod is provided with a suitable handle 45 grip at its lower end and if it is desired to rotate the machine operating shaft continuously the control rod may be held down by hooking the same over a pin 75 (Fig. 1).

Fig. 5 shows the machine at rest with the cores in raised position and with the unset cementitious column supported by a supporting plate 31. This plate is first withdrawn to permit the descent of the cementitious column into the mold section. This 50 plate is carried by horizontal rods 32 which are slidable in the frame members of the machine. To retract the plate to the position shown in Figs. 10 and 6 the main shaft is provided with a cam 33. With

the machine at rest the cam follower on lever 34 is upon the point of cam 33 and descends upon the initial rotation of said cam after the clutch is engaged. Lever 34 has connected thereto a link connecting with a rack 35 slidably mounted in fixed guide 36 (Figs. 5 and 10). Rack 35 upon its descent rotates a pinion 37 fixed to shaft carrying other pinions 38 which mesh with rack teeth on rods 32 thereby retracting the rods 32 and withdrawing the supporting plate 31 from below the lower end of the container. These same parts are used for severing the completed articles upon their restoration to position, as will hereinafter be explained. 75

The column of cementitious material is now ready to descend into the mold section. The cores are arranged to descend preferably concurrently with the descent of the cementitious column by the following mechanism. 80 Straps 40 are attached to the core supporting member 12^a. The straps straddle the shaft 22 and are provided with cam followers which cooperate with lifting and lowering cams 41. The cores descend by gravity as soon as the high point of these cams pass beyond the followers and come to rest upon the pallet 16 (see Fig. 3). Fig. 6 shows the cores just prior to their descent. 85

The descent of the cementitious column into the mold section aids to further compact and unwater the concrete and the outer surface of the column is trowelled during the descent by the sliding of the concrete against the container walls. The descent of the column is facilitated by the concurrent descent of the cores. 90

The cores are now retracted from the mold section by the lifting cams and the protruding section of column cut off by means of a cutting wire 42 which is carried by the rods 32 slightly in advance of the edge of the supporting plate 31. The mold section 15 is slightly spaced from the end 100 of the container 11 to permit the wire to enter and sever the article. The wire may be any one of a multiplicity of forms, such as are shown and described in my copending application Serial No. 275,696. To impart a slight movement of reciprocation to the wire and give a saw-like action thereto in severing the protruding section, I provide the construction shown in Figs. 10 and 11. 110

43 is a wire holder fastened to rods 32. 44 are fixed cams carried by the machine frame and cooperating with rollers 45 suitably mounted in the wire holder frame and having suitable fastening blocks 46 for the wires. Upon the restoration of rods 32 the cams 44 cause the wires to reciprocate back and forth. The wires are maintained taut by the adjusting means 47. 115

In order to divide the article into smaller articles I provide cutter means which in the present embodiment is arranged to effect the 120 125 130

cutting or dividing during the ascending movement of the cores. This cutter means will now be described.

Referring to Figs. 3 and 5, 49 designates a frame work which is mounted to slide up and down relatively to the frame work 10. This frame is connected to the core cross head 12 by means of straps 48 (see Fig. 2). This frame work has extensions which form bearing supports for four shafts 50 which are interconnected so as to rotate in unison by means of bevel gears 51. One of the shafts 50 has fastened thereto a pinion 52 which meshes with a fixed rack 53 (Fig. 3) and thereby imparts a rotational movement to the shafts 50 during the elevation of the frame work. Each shaft 50 carries an eccentric 54 which cooperates with a loop shaped follower 55 (see Figs. 5 and 12). The follower is slotted to permit lateral displacement with respect to the shaft and the cutters 56 and 57 are secured to the follower by studs 58. The cutter wires are preferably fastened to the ends of the studs by nuts 59 and an adjustment 60 is provided for securing the proper tension upon the cutter wires. The cutter wires extend directly across the mold section at right angles to each as shown in Fig. 5, and to permit the elevation and descent of the cutters the mold section is slotted as shown at 61. The arrangement just described is adapted to impart a back and forth saw-like movement to the cutters 56 and 57 during the elevation of the cutter frame and thereby subdivide the larger article into a number of smaller articles of less dimensions. The cutters may be of braided wire or of other forms fully set forth in my copending application Serial No. 275,696. The cutters 56 and 57 as well as cutter 42 may be used for giving a rough uneven surface to the article. This surface is particularly desired in certain products and its advantages are fully set forth in my copending application.

In the embodiment shown the dividing cutters are merely shown diagrammatically. However, these cutters may be of the braided wire or twisted type as shown for the severing cutter in Fig. 11. In fact, any of the cutters may be of any one of the forms shown in my copending application heretofore mentioned, and these cutters will have the specific advantages therein set forth. The cutters are adapted to readily cut the material and leave an open slot between the severed products. They may also impart a desired rough surface to the article.

In Figs. 13 and 14 is shown a modified form of cutter in which the supporting plate 31 is adapted to effect the severing of the cementitious column. The plate may be provided with saw teeth or a roughened edge as shown at 90 or a straight edge may be provided as shown at 91. The plate is adapted

to be longitudinally reciprocated as it is advanced by the cams 44 and for this purpose the plate is slidably supported in brackets 92 carried by the rods 32.

After the article in the mold section has been severed from the column and subdivided and the plate 31 restored to position to support the column of cementitious material in the container, the completed articles should be removed from the mold section prior to the next descent of the cementitious column. Thereafter a new pallet should be brought into position under the end of the mold section. These operations are carried out by the mechanism which will now be described. If desired, a plurality of removable mold sections may be used.

The pallets are advanced under the mold section and the loaded pallets removed by means of a pair of conveyor chains 62 having suitable pallet spacing fingers 63. The chains are intermittently advanced by means of the ratchet and gearing shown at 64. To actuate the ratchet a connecting rod 65 connects the ratchet arms with the end of lever 66 pivoted upon a shaft 67 (see Fig. 3). Lever 66 is provided with a cam follower 68 cooperating with a cam 69 fixed upon shaft 22. This mechanism effects the advance of the conveyor at the proper time to remove the loaded pallet and to bring a new pallet into position below the mold section.

In order to lift the pallets from the conveyor into position below the mold section and thereafter return the same to the conveyor, I provide cams 70 on the main shaft. These cams at suitable times are adapted to allow follower levers 71 to be lowered or raised thereby elevating or lowering pitmen 72. These pitmen at their lower ends slide through swivel blocks 73 carried by crank levers 74. These crank levers are pivoted upon brackets 75 and at their upper ends connect with links 76 which in turn connect with a platform frame 77 which is adapted to support the pallet 16. The platform frame is vertically guided by guide rods 78 (see Fig. 1). Beyond the blocks 73 the pitmen are provided with an additional block 79 and between the blocks are coil springs 80.

The operation of the parts will be best understood by considering a pallet upon the conveyor and afterwards raised into cooperation with the lower end of the mold section and thereafter lowered. With the pallet on the conveyor the pitmen are elevated by their cams and swing the parts from dotted to full line position (Fig. 1) thereby elevating an empty pallet into a position under the lower end of the mold section. It is now necessary to lock the pallet supporting frame into position so as to withstand the shock of the descending cores and cementitious column. This is effected by means of

locking pins 81. These pins are normally spring retracted from locking position in the frame 77 by means of springs 82 and are adapted to be projected forward into locking position by levers 83 pivoted at 84 and having camming surfaces adapted to be engaged by rollers 85 carried by blocks 79. The locking action occurs after the pallet platform is in upper position and the interposed coil springs 80 permit the pitmen to move upwardly in excess of the point necessary to bring the pallet into contact with the mold section. When the pitmen descend, the first movement thereof extends the coil springs 80. Thereafter the pins 81 are projected outwardly to unlock the pallet frame and thereafter the further downward movement of the pitmen lowers the pallet carrying the completed article on the conveyor chain. The chain is then advanced to bring a new pallet into cooperative position and the cycle of operation is repeated.

Certain features of the present invention directed broadly to the severing of the unset column by any means, whether by knives or saw-like cutters, are claimed broadly in my Patent No. 1,358,419. In the present application I claim the machine in combination with saw-like cutting means.

30. I claim:—

1. A machine for making cementitious articles by the column method from an intermittently descending unset cementitious column, comprising power actuated means 35 operating to permit the unset cementitious column to descend upon a pallet, and a cutter means operating in the manner of a saw to sever the lower end of the column.

2. A machine for making cementitious articles by the column method from an intermittently descending unset cementitious column, comprising means operated by the operation of the machine for lowering the unset cementitious column relatively to its container, means operated by the machine for thereafter severing the lower end of the unset column, said severing means comprising cutting wires operating in the manner of a saw.

50. 3. In a machine for making cementitious articles by the column method from an intermittently descending unset cementitious column, comprising means operated by the operation of the machine for lowering the unset cementitious column relatively to its container, means operated by the machine for thereafter severing the lower end of the unset column, said severing means comprising cutting wires operating in the manner of a saw, and cutter means operating in the manner of a saw for thereafter subdividing the severed cementitious article into a plurality of smaller articles.

60. 4. In a machine for the purpose described, 65 in combination, a support for a concrete

article, one or more subdividing cutters composed of twisted wires arranged above the support, and means for raising said cutters through the unset concrete article carried by the support to thereby subdivide the article carried thereby into a plurality of smaller articles.

5. In a machine for the purpose described, in combination, a support for a concrete article, one or more subdividing cutters composed of twisted wires arranged above the support, means for raising said cutters through the unset concrete article carried by the support to thereby subdivide the article carried thereby into a plurality of smaller articles, and means for imparting a back and forth longitudinal saw like movement to said cutters.

6. In a machine for the purpose described, comprising a support for a concrete article, means for intermittently lowering unset concrete articles thereon, one or more subdividing cutters arranged above said support and below the concrete article thereon, and power actuated means for raising said cutter means through the article and for concurrently reciprocaating the said cutters to thereby subdivide the article into a plurality of smaller articles.

7. In a machine of the class described, 95 in combination, a container for a mass of concrete, a mold section below the same, means for intermittently bringing an article supporting pallet below the mold section and for thereafter removing said pallet and replacing the same with a new pallet, means for intermittently causing the unset cementitious column to descend into the mold section and upon said pallet, and means comprising a saw like cutter for periodically 105 severing the portion of the column in the mold section from the superimposed portions of the column.

8. In a machine of the class described, in combination, a container for a mass of concrete, a mold section below the same, means for intermittently bringing an article supporting pallet below the mold section and for thereafter removing said pallet and replacing the same with a new pallet, means for intermittently causing the unset cementitious column to descend into the mold section and upon said pallet, and means comprising a plurality of wire like cutters for subdividing the article in the mold section 115 into a plurality of smaller articles.

9. In a machine for the manufacture of cementitious products, in combination, an upright container for an unset cementitious column, a mold section below the same, a wire like severing cutter for severing the column from the portion imprisoned within the mold section, a supporting plate adapted to periodically support said cementitious column, means for removing the 120

articles from the mold section, and means for actuating said wire like cutter, said plate and said removing means in proper order.

- 5 10. In a machine for the manufacture of cementitious products, in combination, an upright container for an unset cementitious column, a mold section below the same, a plate for periodically supporting the column above the mold section and upon displacement allowing the column to descend into and be retained within said section, core means for descending into and being adapted to be withdrawn from said mold 15 section to thereby form hollow spaces in material therein, a wire like severing cutter adapted to be advanced through the unset cementitious column to sever the material in the mold section from the superimposed 20 cementitious column, means for imparting a reciprocating movement to said wires during said advance, wire like subdividing cutter means adapted to be advanced through the article within the mold section to subdivide the same into a plurality of smaller 25 articles, means for reciprocating said last mentioned cutter means, means for removing the completed articles and means for operating said cutters, said supporting 30 plate, and removing means in proper order.

11. In a machine for making cementitious articles from an intermittently descending unset cementitious column formed in a con-

tainer, comprising means operated by the machine for lowering the unset cementitious column relatively to the container, means for thereafter severing the lower end of the cementitious column, and cutter means operating in the manner of a saw for thereafter subdividing the severel article into a plurality of smaller articles.

12. In a machine for making cementitious articles from an intermittently descending cementitious column by the column method, in combination, a power driven shaft, a supporting plate for the unset cementitious column, means driven by said shaft for shifting said plate, a cutter means of the wire type adapted to be advanced through the unset column for severing the same, said cutter means being operated by said shaft in timed relation to the descent of the column.

13. In a machine for making cementitious articles by the column method from an intermittently descending unset cementitious column comprising power actuated means operating to permit the unset cementitious column to descend upon a pallet, cutter means operating in the manner of a saw to sever the lower end of the column and means associated therewith for thereafter supporting the superimposed severed unset column.

In testimony whereof I hereto affix my signature.

ALFRED OWEN CROZIER.
